UNITED STATES PATENT OFFICE.

BERT H. SMITH AND WILLIAM A. INWOOD, OF FAIRBURY, NEBRASKA, ASSIGNEES TO THE WILLBERT MANUFACTURING COMPANY, OF FAIRBURY, NEBRASKA, A CORPORATION.

OILING DEVICE.

1,230,936.

Specification of Letters Patent. Patented June 26, 1917.

Application filed April 11, 1916. Serial No. 90,428.

To all whom it may concern:

Be it known that we, BERT H. SMITH and WILLIAM A. INWOOD, citizens of the United States of America, residing at Fairbury, in the county of Jefferson and State of Nebraska, have invented certain new and useful Improvements in Oiling Devices, of which the following is a specification.

This invention relates to new and useful improvements in oiling devices and more particularly to oiling devices for reciprocating pistons and valve stems in steam, oil, and air engines and pumps and the primary object is to provide a means for applying hard oil, commonly known as pin grease, thereto.

Still another object of the invention resides in providing a casting formed of two sections and adapted to be secured to the piston removably, the casting being provided with an annular passage for grease which is designed to flow radially to the piston or stem on which the device is applied.

A still further object resides in providing a device which is simple and durable in construction, inexpensive to manufacture and one which will be very efficient and useful in operation.

With these and other objects in view, our invention consists in the novel features of construction, combination and arrangement of parts as will be hereinafter referred to and more particularly pointed out in the specification and claims.

35 In the accompanying drawing forming a part of this application:—

Figure 1 is a side elevation of a device constructed in accordance with my invention;

40 Fig. 2 is a plan view thereof; and

Fig. 3 is a section as seen on the line 3—3 of Fig. 2.

In describing the invention we shall refer to the drawing in which similar reference characters designate corresponding parts throughout the several views and in which 1 and 2 designate semi-annular sections of a metallic casting, the latter being annular and designed to fit closely on a piston, valve stem or other movable shaft of like character, the inner periphery of the same being concaved as shown at 2^a in the drawing.

The sections of the casting are provided at their ends with lateral lugs 3 which afford means whereby bolts 4 may be engaged

therewith to secure the sections together and formed integral with the casting and projecting radially therefrom are the lugs or tongues 5 in which are provided openings for guide purposes or which afford means whereby the castings may be secured in place, if desired.

The sections 1 and 2 of the casting are each provided with a channel or passage way 6 which is formed centrally thereof and when said sections are secured together a complete annular channel or passage way is formed which provides a grease channel in the casting. Extending transversely through the sections of the casting are a plurality of radial channels or passage ways 7 which afford communication between the passage or channel 6 and the concaved inner periphery of the casting. It may be here stated that this concaved portion 2^a is only arranged about centrally of the inner periphery so as to form an annular channel or socket around the piston, upon which the device is applied.

Formed integral with the section 2 of the casting and projecting radially therefrom is a cylindrical socket member 8 which is internally threaded and the interior of said socket member is adapted for communication with the annular channel or passage 6 through the medium of a channel or passage way 9. The socket 8 forms a reservoir for the grease or hard oil and the latter is adapted to be forced through the channel 9 into the annular passage 6 by means of a plug 10 which is threaded into engagement with the threaded socket 8. The plug 10 has a squared socket 11 in its outer end whereby the same may be engaged with an instrument for the operation of said plug and it is obvious that the grease may be forced into the passage 6 by forcing inwardly on the plug. In this manner the piston or valve stem may be perfectly lubricated at all times.

From the foregoing it will be seen that I have provided a simple, inexpensive and efficient means for carrying out the objects of the invention and while I have particularly described the elements best adapted to perform the functions set forth, it is obvious that various changes in the form, proportion and in the minor details of construction may be resorted to without departing from the spirit or sacrificing any of the principles of the invention.

Having thus described our invention, what we claim and desire to secure by Letters Patent is:—

1. A lubricating device including an annulus provided with an inclosed annular grease passage therein, the inner periphery of the annulus being provided with an annular groove and means for feeding the contents of the passage to the groove. 50
2. In a lubricating device, an annular member provided with an inclosed annular passage therein and having the inner periphery concave, said member being also provided with a plurality of radial channels affording communication between the passage and the inner surface and means for feeding grease to the passage and said concave inner periphery. 55
3. In a lubricating device, an annular member having an annular passage therein and having its inner periphery provided with an annular groove, said passage communicating at various points with the annular groove in said member, a grease reservoir formed on said member and communicating with said passage, and means for feeding the contents of said reservoir to said passage and correspondingly to the groove in the inner periphery. 60
4. In a lubricating device, an annular member provided with an annular groove in its inner surface and further provided with an annular passage within the same, said passage having communication at various points with the groove, a socket member formed integral with the outer periphery of said member and having communication with said passage, and means for feeding the contents of the socket to the passage and correspondingly to said groove. 65
5. In a lubricating device, an annular member formed of sections removably secured together and having the inner periphery thereof provided with an annular groove, said member being also provided with an internal annular passage having communication at various points with the

groove, a socket member formed integral with and projecting from the outer periphery of said member, said socket member being internally threaded and having communication with said passage, and a plug movably engaged with said socket for feeding the contents of the latter to said passage and correspondingly to said groove. 55

6. A lubricating device for piston rods and the like comprising a ring provided with an annular grease-containing passage within the body thereof between its inner and outer periphery, the inner periphery of said ring being provided with an annular groove communicating with said passage, said ring having an exteriorly open grease-containing chamber communicating with said passage and means in said chamber for forcing grease into the passage and into said groove. 60

7. A lubricating device for piston rods and the like comprising a sectional ring having an annular grease-containing passage within the body thereof between its inner and outer periphery and having an annular groove in its inner periphery communicating with said passage, means for securing said ring in position, and means on said ring for forcing grease into said passage and said groove. 70

8. A lubricating device for piston rods and the like comprising a sectional ring having an annular grease-containing passage within the body thereof between its inner and outer periphery and having an annular groove in its inner periphery communicating with said passage, said ring having integral attaching lugs and means on said ring for forcing grease into said passage and said groove. 75 80

In testimony whereof we affix our signatures in the presence of two witnesses.

BERT H. SMITH.
WILLIAM A. INWOOD.
